ELECTROMAGNETIC CLOCK WINDING
MECHANISM

Sylvanus W. Bramley, White Plains, N. Y.

Application October 28, 1944, Serial No. 560,738

4 Claims. (Cl. 185—40)

1

This invention relates to electromagnetic clock winding mechanism.

The invention is in the nature of an improvement on my copending application Serial No. 539,945, filed June 12, 1944, now Patent No. 2,412,077. As shown in that application, the clock mechanism is operated by the rotation of an armature actuated by a spring. When the armature reaches a predetermined position corresponding to a run-down condition of the mechanism, it is necessary to restore the desired amount of energy in the spring by a movement of the armature in the opposite or counterclockwise direction. As set forth in said prior application, this is accomplished by the closing of an electrical circuit, specifically by the action of contact mechanism carried and actuated by the said armature. It has been found that it is of the greatest importance that the closing of the electrical circuit by the said contact or switch mechanism should be complete, positive and instantaneous. If this is not the case, the operation of the mechanism is not as reliable and accurate as is desired.

One of the principal objects of this invention is to devise improved means for accomplishing this purpose. Another principal object of the invention is to provide improved means for maintaining complete and satisfactory contact closing conditions during rewinding of the mechanism.

These and other objects will be apparent from the following description taken in conjunction with the accompanying drawings in which

Figures 1, 2, and 3 show that part of the clock mechanism with which the present invention is concerned.

Figures 4 to 10 show the details.

Figure 1 is a view with the cover of the clock removed showing the armature in its run-down condition and in relation to the electromagnet,

Figure 2 is a view similar to Figure 1 showing the armature in its wound-up condition.

Figure 3 is a view similar to Figure 1 with the electromagnet removed so that the underlying mechanism can be more clearly seen.

Figure 4 is a perspective view showing in enlarged detail the snap switching mechanism.

Figure 5 is an enlarged view of a portion of the armature showing the position of the automatic switch closing structure at the instant of its closing and when the armature is in a run-down position.

Figure 6 is a view similar to Fig. 5 showing the mechanism when the armature is in its wound-up position.

Figure 7 is a sectional view on the line 7, 7 of Figure 1.

Figure 8 is a view similar to Figure 7 showing one of the parts in a different position.

Figure 9 is a view taken on the line 9, 9 of

2

Figure 7 and looking in the direction of the arrows, and

Figure 10 is a view taken on the line 10, 10 of Figure 9 and looking in the direction of the arrows.

In the several views the same parts are shown by the same numerals.

The dial or face member 1 supports a plate 2. This plate supports posts not specifically shown to which the yoke 3 or bridge member is secured by means of screws 5, 5a. One end of a fixed mandrel 6 is anchored in the bridge member of yoke 3, and on this mandrel there is rotatably mounted a hollow drum 7 carrying on the inside thereof the main spring 7a, shown in dotted lines. The armature 9 having end pieces 9a, 9b is also rotatably mounted on said mandrel 6 and is recessed to provide a space which receives the said drum 7. The latter has a ratchet wheel circumference 7b and is connected with the armature 9 through pawl 10. By rotating the drum 7 in relation to the armature 9, the main spring 7a may be given a normal or minimum tension and then additional energy is supplied to said spring by the intermittent rotation of the armature 9 caused by the corresponding intermittent energization of the electromagnet. Also rotatably mounted on said mandrel 6 is another ratchet wheel 8 which cooperates with pawls 15, 15a mounted on the armature 9. Rotation of the ratchet wheel 8 causes operation of the clock mechanism which mechanism may be of the conventional type and is therefore not shown.

The armature 9 also carries an extension or ear 25, on which is secured pivot pin 26. On this pin 26 there is pivotally mounted snap switching mechanism employing the toggle principle. This includes a lever 28 having an upstanding bracket portion 42 and rotatably or pivotally secured on the pin 26 by means of ring 29. The lever 28 has a recess or notched portion 41 which receives one end of a resilient strip or spring toggle member 40, the other end of which is secured to bar 39 at the joint 30. The bar 39 is secured to armature 9 at the point 39a.

The bar 39 is resilient and biases the spring member 40 in the notch 41. It will be seen that when the lever member 28 is turned so that the line of application of the biasing force lies to the left or the right of center line 34, that the lever member 28 will be snapped by the energy in the spring member 40.

As specifically shown in the drawings, the upstanding bracket 42 carries a presser bar 43 which cooperates with an elongated contact member indicated generally as 47, said presser bar 43 which is part of the toggle switch mechanism, operating to snap said contact 47 into switch or circuit closing position when the armature 9 has reached its run-down position. When the circuit is closed, the arm or contact member 47 bridges two pure

silver contacts 58, 58a which are spaced apart and connected to metallic strips 57, 51a separated by insulation 55, the said spaced contact, strip and insulation being mounted upon an insulating cover plate 56 made of any suitable insulating composition. The cover plate 56 is supported on posts 66 and the electromagnet 11 is secured to and suspended from said cover plate and lies just above the yoke 3 so that the end pieces 9a, 9b of the armature sweep over the pole pieces 11a, 11b of the electromagnet during rotation of the armature.

The contact arm indicated generally as 47 is secured by screws 48 to a bracket 46 which is also pivoted on the pin 26 carrying spring 49 which biases the bracket 46 and contact arm 47 secured thereto, so that said contact 47 is normally urged away from the spaced contacts 58, and 58a. It will be seen that the said contact arm 47 because of its mounting on the pin 26 supported on the extension 25 of armature 9, is so arranged in relation to the spaced contacts 58, 58a, that when the pivot 26 is moved through an arcuate path by rotation of the armature to its run-down position, said contact arm 47 is then in a position where a swinging or rotative movement of said contact arm 47 about the pivot 26 causes engagement of said contact arm 47 with the silver contacts 58, 58a at a point intermediate between the ends of said contact arm 47 (see for example Figs. 1 and 2, also Fig. 4). The contact arm 47 is held by electromagnetic attraction of the electromagnet 11, in circuit closing position in which position the said contact arm 47 bridges the pure silver contacts 58, 58a and the said arm 47 will remain in said circuit closing position as long as the electromagnet is energized. When the armature 9 is rotated under the pull of the electromagnet, the contact arm 47 is wiped across the silver contacts 58, 58a. When the armature is rotated to its fully wound-up position (note Fig. 2) the arm 47 is caused by that movement to be disengaged from contact with said spaced contacts 58, 58a and the electrical circuit including the electromagnet and said spaced contacts 58, 58a is thus broken and the arm 47 biased away from the contacts 58, 58a by spring 49. The armature is then free to be rotated under the urge of the main spring since the magnet is then deenergized. It may be stated at this point that the said arm 47 is free to rotate through a small arc or angle which may be suitably limited, as for example, by means of guide pieces 59, 59a secured in the cover plate 56 in cooperation with a recess 56b in said cover plate, forming an elongated slot to receive the elongated arm 47.

The invention includes special means for obtaining and maintaining suitable, positive, and instantaneous switch closing action, including not only the previously mentioned toggle switch mechanism but also certain structure of the contact arm 47. It will be seen that the arm 47 comprises a member which is split longitudinally to provide two legs 47a and 47b. These are thin resilient strips made of soft iron which cooperate with a soft iron shoe 10a attached to the pole piece 11a of the magnet. To the legs 47b there is secured a resilient strip preferably made of bronze, brass or the like, this strip 50 being secured at one end by screw 48 and at the other end by being bent around the end of the strip 47b to form a hook or loop as shown in Fig. 4. The bronze strip 50 is also spaced somewhat from the strip 47b to provide a cushion effect. To each of the strips 47a and 50 there is secured by braz-

ing or otherwise two V-shaped bars 51, 51a and it will be seen that the bar 51 (note Fig. 8) is in a position advanced toward the contacts 58, 58a more than the bar 51a. In operation therefore the contacts 58, 58a are not bridged at precisely the same infinitesimal increment of time but rather the contact 58a first is engaged by the bar 51 and then the bar 51a engages the contact 58, it being also noted that the trigger or toggle action of the presser bar 43 (see dotted line, Fig. 9) serves to instantaneously snap the bar 51a into contact with the contact 58.

Owing to the V-shaped arrangement of the bars 51, 51a there is an improved maintenance of electrical contact or circuit closing conditions during rotation of the armature from the position shown in Fig. 1 to the position shown in Fig. 2, that is, from a run-down to a wound-up position of the armature.

Regarding the operation of the device and assuming that the armature has been rotated to its wound-up position as indicated in Fig. 2 and that the electrical circuit has thereby been broken by disengagement of the arm 47 with the spaced contacts 58, 58a, the armature is then free to rotate under the urge of the main spring 7a. At that time the lever 28, spring toggle member 40, presser bar 43 and the arm 47 are in the positions indicated in Figs. 6 and 4, the presser bar 43 having been snapped to its release position and the arm 47 having been spring-urged away from spaced contacts 58, 58a. Now as the lever 28 rotates together with the armature 9, extension 25 and pin 26 on which said lever 28 is mounted, the lug 36 on the lever 28 engages the lug 31 on the yoke 3 as shown in Fig. 6, whereby the lever 28 is turned. This turning occurs when the armature is in the run-down position as shown in Figs. 1 and 5, and the said turning of the lever 28 has the effect of snapping the switch, that is, the lever 28 is snapped into the position shown in Fig. 5 thereby snapping the presser bar 43 against the contact member indicated generally as 47 and causing positive and instantaneous closing of the electrical circuit. As the armature starts to rotate under the pull of the electromagnet toward its wound-up position and in the direction of the arrows in Fig. 5, the lug 36A on the lever 28 engages the lug 37 on the yoke 3. This turns the lever 28 and the toggle action then snaps the lever into released position as shown in Fig. 6 although this release occurs before the lever 28 is tripped, said release occurring by the said turning action of the lever 28. During this time the bars 51, 51a are being wiped across the silver contacts 58, 58a by a combination of transverse and longitudinal motion as a result of the V-shaped arrangement of the bars 51, 51a. This wiping movement is caused by the movement of the pin 26 on the extension 25 of the armature 9, said pin moving to an arcuate path and pulling the pivoted arm 47 through a path confined between the guide pins 59, 59a. During this movement the presser bar 43 has been moved into released position by the turning of the lever 28 caused by engagement of lugs 36, 37 and when the armature is in its wound-up position as shown in Fig. 2 the end of the arm 47 is pulled away from the silver contacts 58, 58a, the electrical circuit is broken and the arm 47 is biased away from said contacts 58, 58a by spring 49. It will be clear that numerous modifications may be made within the scope of the principles and disclosure herein set forth. A considerable number of variations of the toggle mechanism specifically shown may

be employed, for example, the resilient strip 49 could be pivoted to the lever 28 and might be a rigid member connected to a coil spring secured to the armature 9. The specific toggle mechanism shown has been found to be satisfactory but is merely one embodiment of the principle thereof as applied in the present environment. The invention includes the effect of the toggle switch, the lever of which is automatically thrown by engagement with any suitable means carried by the body of the clock mechanism. In the structure specifically shown, e. g., Figs. 5 and 6, the turning of the lever is by engagement thereof with a lug 37 on the yoke 3. It will be clear that the lever 28 could be turned by other equivalent and automatic means, the invention involving the provision of said automatic turning caused by rotation of the armature on which the pivoted lever 28 is mounted. The invention is not necessarily limited to the use of the contact arm 47 in combination with the presser bar 43 specifically shown as part of the toggle trigger switch mechanism because in some cases the switch can be closed and maintained in its closed position and opened by the toggle switch mechanism without the interposition of arm 47. Such arm is however advantageous particularly when provided with the structure illustrated in Figs. 7 to 10 inclusive, because said arm assists in maintaining the electrical circuit in closed condition during rotation of the armature from the run-down position to the wound-up position.

What is claimed is:

1. In clock mechanism of the character described including an armature arranged to be rotated to a run-down position by the energy of the main spring and to a wound-up position by the action of an electromagnet upon the closing of an electric circuit, the improved means for closing said circuit upon rotation of said armature to said run-down position which comprises toggle switch mechanism including a spring-biased toggle element and a switch arm pivoted on said armature and means engaging said element to trip the toggle and snap the switch arm into closed circuit condition, upon rotation of said armature and toggle element into the run-down position of said armature, said switch arm on being snapped to a closed position engaging one of the poles of said electromagnet, said electromagnet holding said toggle switch mechanism in a circuit-closing position until said armature is moved to a wound up position.

2. In clock mechanism of the character described including an armature arranged to be rotated to a run-down position by the energy of the main spring and to a wound-up position by the action of an electromagnet upon the closing of an electric circuit, the improved means for closing said circuit upon rotation of said armature to said run-down position which comprises toggle switch mechanism including a spring-biased toggle element pivoted on said armature and a switch arm pivotally mounted on said toggle element and means engaging said element to trip the toggle and snap said switch arm into closed circuit condition upon rotation of said armature and toggle element into the run-down position of said armature said switch arm on moving to a closed position engaging one of the poles of said electromagnet, said electromagnet holding said switch arm in a closed position until said armature reaches a wound up position.

3. In clock mechanism of the character described including an armature arranged to be ro-

tated to a run-down position by the energy of the main spring and to a wound-up position by the action of an electromagnet upon the closing of an electric circuit, the improved means for closing said circuit upon rotation of said armature to said rundown position which comprises a pair of fixed switch contact members, a pivot on said armature, a switch arm pivoted on said pivot, said arm being arranged to move by an arcuate movement of said pivot into a position where rotation of said switch arm causes it to engage said contacts and close said circuit, said arm being normally biased away from said contacts and into open circuit position, and means to snap said switch arm into engagement with said contacts, said means including a spring-biased toggle element pivotally mounted on said pivot and carrying a presser bar, and means on said toggle element and cooperating means on the body of the mechanism to trip said toggle element and cause the presser bar to snap said switch arm into engagement with said fixed contacts upon rotation of said armature and toggle element to the run-down position of said armature and to release said presser bar and permit said arm to be biased into open circuit position upon rotation of said armature into a wound-up position, said switch arm on being moved to a closed position engaging a portion of one of the poles of said electromagnet, said switch arm being held in engagement with said contact members by said electromagnet as said armature moves toward a wound up position, said switch arm sliding across said contact members as said armature moves toward a wound up position and sliding off said contact members to break the circuit to said electromagnet when said armature reaches a wound up position.

4. In clock mechanism of the character described including an armature arranged to be rotated to a run-down position by the energy of the main spring and to a wound-up position by the action of an electromagnet upon the closing of an electric circuit, the improved means for closing said circuit upon rotation of said armature to said run-down position which comprises toggle switch mechanism including a spring-biased toggle element pivoted on said armature and a switch arm pivotally mounted on said toggle element, a pair of contact points, and means engaging said element to trip the toggle and snap said switch arm into closed position upon rotation of said armature and toggle element into the run-down position of said armature and spring means biasing said switch arm away from a closed position toward contact with said toggle element, and a resilient contact member mounted on said switch arm for engaging said contact points.
